UNITED STATES PATENT OFFICE.

DANIEL ROUNDS AND CLARENCE E. COOK, OF PORTLAND, MAINE.

REPAIR-LAST.

No. 877,519.

Specification of Letters Patent.

Patented Jan. 28, 1908.

Application filed April 15, 1907. Serial No. 368,231.

To all whom it may concern:

Be it known that we, DANIEL ROUNDS and CLARENCE E. COOK, citizens of the United States, and residents of Portland, in the 5 county of Cumberland and State of Maine, have invented new and useful Improvements in Repair-Lasts, of which the following is a specification.

Our invention relates to improvements in 10 repair lasts. It is designed to make a strong, durable last which can be readily adjusted in the shoe and which can be readily inserted in and removed from the shoe.

In the drawings herewith accompanying 15 and making part of this application, Figure 1 is an elevation of our improved last, parts being broken away to expose the operating mechanism; Fig. 2 is a top plan view of the same, parts being broken away to expose the operating 20 mechanism; Fig. 3 is a transverse sectional view taken on a vertical line passing through the pivot points in the heel part.

Same letters of reference refer to like parts.

25 In said drawings A and B represent the heel and toe parts respectively of a divided last, said parts being preferably made of metal and hollow. The heel part is pivotally mounted upon a bearing block C by 30 means of pivot points D passing through the walls of the last and taking into sockets E in said block. Rigidly secured to the toe part in any convenient manner is a corresponding bearing block F. As shown this bearing 35 block has a bifurcated projection G through which passes a holding bolt H having a shoulder I thereon adapted to engage against the projection G; the threaded end J of the bolt taking into the bottom of the last as seen 40 in Fig. 1. The upper end K of said bolt is adapted to receive a wrench or screw driver for operating it. Slidably mounted in blocks C and F are parallel rods L. Connecting said rods L midway their length is a strap M. 45 Blocks C and F are connected by a toggle comprising a head piece N and links O and P connecting said head piece with blocks C and F respectively. A toggle operating bolt Q properly threaded passes through parts N 50 and M and in threaded engagement therewith. Said bolt is provided with an angu-

lar head adapted to receive an operating wrench S.

The operation of our improved last is as follows: To insert the last in the shoe the 55 adjacent edges are brought together by contracting the toggle and then the heel part A is tipped upwardly on its pivot thus contracting the last to its shortest extent and rendering it easily inserted in the shoe. 60 After it is inserted in the shoe the heel part is tipped back into normal position and the last expanded by expanding the toggle. The two parts of the last slide to and from the central strap M on the parallel rods L accord- 65 ing as the toggle is expanded or contracted.

The advantages of our last are that it is strong and durable and readily inserted in and removed from a shoe. The last is adjustable in the shoe and the heel part is 70 capable of being tipped on its pivot at any point in its adjustment.

Having thus described our invention and its use we claim:—

1. A two part last comprising hollow heel 75 part, a block pivotally mounted entirely within said hollow part, a hollow toe part having a bearing block rigidly mounted entirely within said hollow part, parallel rods slidably mounted in said bearing blocks, a toggle 80 connecting said bearing blocks and means for operating said toggle.

2. A two part last comprising a hollow heel part having a bearing block pivotally mounted entirely within said hollow heel 85 part, a hollow toe part provided with a bearing block rigidly mounted entirely within said hollow toe part, parallel rods slidably mounted in said bearing blocks above the bottom of said last parts, a strap connecting 90 said parallel rods, a toggle connecting said bearing blocks and a toggle operating bolt mounted in said toggle and said strap.

In testimony whereof, we have signed our names to this specification in presence of 95 two subscribing witnesses this twelfth day of April, 1907.

DANIEL ROUNDS.
CLARENCE E. COOK.
